US00D779620S

(12) **United States Design Patent** (10) **Patent No.:** **US D779,620 S**
(45) **Date of Patent:** **** Feb. 21, 2017**

(54) **ENHANCED MAGAZINE RELEASE**

(71) Applicant: **George Huang**, Henderson, NV (US)

(72) Inventor: **George Huang**, Henderson, NV (US)

(**) Term: **15 Years**

(21) Appl. No.: **29/549,829**

(22) Filed: **Dec. 28, 2015**

(51) LOC (10) Cl. **22-01**

(52) U.S. Cl.

USPC **D22/108**

(58) **Field of Classification Search**

USPC D22/108, 100, 104, 199; 42/6, 7, 49.1,
42/42.5, 42.51; D11/218

(57) **CLAIM**

The ornamental design for an enhanced magazine release, as shown and described.

DESCRIPTION

FIG. 1 is a right, rear, upper perspective view of the first embodiment of an enhanced magazine release, showing my new design;

FIG. 2 is a right, rear, lower perspective view thereof;

FIG. 3 is a left, upper perspective view thereof;

FIG. 4 is a left, lower perspective view thereof;

FIG. 5 is a front, upper perspective view thereof;

FIG. 6 is a front, lower perspective view thereof;

FIG. 7 is a rear, upper perspective view thereof;

FIG. 8 is a rear, lower perspective view thereof;

FIG. 9 is a top view thereof;

FIG. 10 is a bottom view thereof;

FIG. 11 is a front view thereof;

FIG. 12 is a rear view thereof;

FIG. 13 is a left side view thereof;

FIG. 14 is a right side view thereof;

FIG. 15 is a right, rear, upper perspective view of the second embodiment of an enhanced magazine release, showing my new design;

FIG. 16 is a right, rear, lower perspective view thereof;

FIG. 17 is a front, upper perspective view thereof;

FIG. 18 is a front, lower perspective view thereof;

FIG. 19 is a left, upper perspective view thereof;

FIG. 20 is a left, lower perspective view thereof;

FIG. 21 is a right, upper perspective view thereof;

FIG. 22 is a right, lower perspective view thereof;

FIG. 23 is a top view thereof;

FIG. 24 is a bottom view thereof;

FIG. 25 is a left side view thereof;

FIG. 26 is a right side view thereof;

FIG. 27 is a rear view thereof; and,

FIG. 28 is a front view thereof.

(Continued)

The broken lines shown throughout the various figures depict additional structures that form no part of the claimed design.

1 Claim, 14 Drawing Sheets
